UNITED STATES PATENT OFFICE.

WORTHY C. BUCKNAM, OF JERSEY CITY, NEW JERSEY, ASSIGNOR TO DAVIS-BOURNONVILLE COMPANY, OF NEW YORK, N. Y., A CORPORATION OF NEW YORK.

TORCH CUTTING-MACHINE.

1,324,005.

Specification of Letters Patent. Patented Dec. 2, 1919.

Application filed May 31, 1918. Serial No. 237,413.

To all whom it may concern:

Be it known that I, WORTHY C. BUCKNAM, a citizen of the United States, and a resident of Jersey City, in the county of Hudson and State of New Jersey, have invented a new and useful Torch Cutting-Machine, of which the following is a specification.

The invention relates to certain improvements in center standard, swinging arm gas-cutting machinery, and comprises specifically, though not necessarily exclusively, an improved machine for cutting upstanding flanges or along templets of like character, the same being an improvement upon and within my prior Patent 1,172,933 of Feb. 22, 1916.

The objects are to secure firmness of support with complete flexibility of movement, durability, and compactness, to make possible reliable guiding upon a flange and accurate and continuous cutting, and to enable the apparatus to be conveniently engaged and disengaged from the flange. To these ends the invention may be said to consist in the parts, improvements and combinations hereinafter described and more particularly pointed out in the claims, it being understood that parts of the invention are not limited to the particular illustrative embodiments.

In the drawings forming a part hereof:

Figure 1 is a side elevation of the machine in condition for use;

Fig. 2 is a sectional end elevation; and

Fig. 3 is an enlarged side elevation of the guiding and torch-bearing structure.

A pedestal 1 carries a vertical post 2, which can be raised and lowered and held at any height by mechanism designated generally 3. A vertical hub member or center frame 4, mounted rotatably between collars 5 on the post 2, carries a rigid radial arm 6. This arm is preferably composed of a pair of rods 7 spaced vertically by strut 8 and connected at their outer ends by a terminal piece 9. The long trussed overhanging arm thus constituted is braced by a stay-rod 10 with turnbuckle 11 extending diagonally from the upper end of the hub member 4 to the terminal piece 9.

The rods 7 form longitudinal guides for upper and lower, fore and aft grooved rollers 12 journaled in a carriage 13, which may be made of two vertical halves or frames secured together by the axles of said rollers at opposite sides of the arm. Handles 14

on the carriage enable it to be readily moved to a desired position on the arm.

An electric motor 15 is planted upon the top of the carriage 13. Its armature shaft 60 is preferably arranged transversely and provided beyond one side of the carriage with a worm 16, which meshes with a worm wheel 17 on the upper end of a vertical shaft 18 mounted in lateral bearings 19 on the 65 carriage. On the lower end of said vertical shaft is another worm 20, meshing with a worm wheel 21 on a transverse shaft 22. Said transverse shaft is journaled in bearings in lateral arms 23 carried by the central portion of a bracket 24 of V-shape or other suitable open form which projects downward from the carriage 13. A vertical shaft 25 is supported revolvably in a central bearing in said bracket and at its upper end above the central part of the bracket has a bevel gear 26 meshing with another bevel gear 27 on the shaft 22. On the lower end of said vertical shaft is a horizontal driving wheel 28 which travels upon the 75 outer side of the flange 29.

A sleeve 30 is swiveled on or about the shaft 25 between collars 31, and a rearwardly extending arm 32 is hingedly connected to the vertical swivel by a transverse pivot 33. A rod 34 projecting downward from the hinged arm 32 adjacent its pivot bears a pair of horizontally spaced rollers or wheels 35, which are urged by the weight of said arm and the parts carried thereby 90 to bear upon the inner side of the flange in opposition to the driving wheel 28. Said rollers 35 are mounted upon the end portions of a cross-arm 36, which may be swiveled upon the lower end of the rod 34, and are in substantially equidistant lateral relation to the axis of the driving wheel.

The arm 32 carries horizontal and vertical torch adjusters, which in turn carry a downwardly extending arm 39 terminating 100 in a torch-holding sleeve 40. The arm 39 is angled or directed inward in order to bring the tip 41 of the cutting torch 42 intermediate projections of the axes of the pressure rollers 35 and at or adjacent the 105 transverse vertical plane which intersects the axis of the driving wheel. The torch is shown held substantially horizontal, with its tip deflected upward to cut the flange off on a bevel. The angle may be varied by changing the tip, and also by loosening the screw 43 and turning the arm slightly about 110

it as an axis. A tube 44 having a flaring basal flange 45 placed over the shaft 25 immediately above the driving wheel 28 protects said shaft and wheel from injury by the jets.

The torch-adjusting devices include a carriage 37 mounted to slide horizontally on the arm 32 under the control of a screw 38 having a handwheel 46. A second carriage 10 47 slides vertically on the horizontal carriage, being actuated by a screw 48 which has a laterally projecting handwheel and shaft 49 geared to it as indicated at 50. The torch arm 39 is secured to the lower part 15 of the vertical carriage 47.

From the foregoing it will be perceived that the depending structure as preferably constituted comprises two parts embracing the flange, a primary part which includes 20 the vertical drive-shaft 25 and the feed wheel 28, and a secondary part flexibly connected to the primary part and carrying the torch, the torch-adjusters and the pair of pressure wheels 35, which bear by gravity upon the flange in opposition to the driving wheel.

If the machine is used to trim the flange of a boiler head 51, for example, its pedestal may be placed upon the approximate 30 center of the inner face of the head, and the carriage 13 is moved upon the radial arm 6 to a position over the upstanding flange. By lifting the inner part of the depending torch-bearing and flange-embracing structure about the axis 33, the pressure rollers 35 can be caused to clear the top of 35 the flange. In operation, the weight of this part, supplemented by an additional weight if desired, acts to hold the said rollers against 40 the inner face of the flange, and consequently the driving roll 28 against the outer face, with substantial pressure, so that adequate traction is insured. The torch is then adjusted to the desired height and distance 45 from the flange, its heating jet is lighted and the oxygen cutting jet turned on, and the driving motor 15 is started. This causes the driving wheel to revolve in contact with the outer face of the flange and thus to propel 50 the torch around its circuit.

In order to avoid moving the machine, the head 51 or other part to be operated upon may be placed entirely at one side of the pedestal, so that the machine does not 55 stand upon the work. In that event, the driving wheel 28 acts upon the inner side of the flange, and the pressure wheels 35 and the torch are disposed at its outer side. Under such conditions a section of the flange 60 is trimmed, the cutting is stopped and the work is shifted in order to bring another section of the flange within the range of the torch. The machine may also be used to trim flanges of smaller extent surrounding 65 internal openings in a boiler-head or

the like. In any case the free movement in and out of the carriage 13 upon the radial arm 6 enables the torch-bearing structure to follow the flange irrespective of its form or eccentricity.

While the machine is primarily intended for trimming off upstanding flanges or metal walls, it will be apparent that it may be used for other purposes either in the illustrated or in modified form. For example, 75 the flange, which is in fact a guide or templet, may be substituted by a special templet, and the torch, which in trimming flanges will be directed laterally or at an inclination, may be pointed downward by 80 turning its arm.

What I claim as new is:

1. A machine for cutting in various directions by means of gases comprising, in combination, a center support, a radial arm 85 swinging upon the center support and presenting a longitudinal guide-way, a carriage movable freely on the guide-way, a torch and a feed wheel carried by the carriage, and power means for driving the feed wheel, 90 whereby the carriage moves automatically in and out on the arm and swings the same in accordance with the course pursued by the feed wheel.

2. A machine for cutting in various directions by means of gases comprising, in combination, a center support, a radial arm swinging upon the center support and presenting a longitudinal guide-way, a carriage 95 movable freely on the guide-way, a torch and a feed wheel carried by the carriage, and a motor and gearing for driving the feed wheel carried wholly by the carriage, whereby the carriage moves automatically in and 100 out on the arm and swings the same in accordance with the course pursued by the feed wheel.

3. A machine of the character described, comprising a center support, an overhanging radial arm swinging thereon, a carriage 110 freely movable on longitudinal guides on said arm, and a depending torch-bearing structure on the carriage having a feed wheel and adapted to travel on an upstanding flange and means for driving the feed wheel, 115 whereby the carriage moves in and out on the radial arm in obedience to the course pursued by the self-propelled structure along the flange.

4. A machine for trimming upstanding 120 flanges by means of gases, having a center support, a depending self-propelled structure and means for supporting the same from the center with freedom to swing about the center and to move in and out with reference thereto as the depending structure travels along the flange, said depending structure having a driven feed wheel on a vertical axis, and torch-supporting means arranged to cause the torch to deliver its 130

jets in substantially constant relation adjacent the vertical region of driving upon the flange.

5. A machine for trimming upstanding flanges by means of gases, having a center support, a depending self-propelled structure and means for supporting the same from the center with freedom to swing about the center and to move in and out with reference thereto as the depending structure travels along the flange, said depending structure comprising primary and secondary wheeled parts embracing the flange between them, the secondary part bearing a torch and torch-adjusters and freely hinged to the primary part to bear by gravity against the flange.

6. A machine for trimming upstanding flanges by means of gases, having a center support, a depending self-propelled structure and means for supporting the same from the center with freedom to swing about the center and to move in and out with reference thereto as the depending structure travels along the flange, said depending structure comprising a primary part including a vertical drive shaft with a feed wheel upon its lower end, and a secondary part suspended flexibly from the primary part and carrying a torch and torch adjusters and a pair of pressure wheels adapted to bear upon the flange in opposition to the feed wheel.

7. A machine for trimming upstanding flanges by means of gases, having a center support, a depending self-propelled structure and means for supporting the same from the center with freedom to swing about the center and to move in and out with reference thereto as the depending structure travels along the flange, said depending structure comprising a primary part including a vertical drive shaft with a feed wheel upon its lower end, and a secondary part comprising an arm hinged to the primary part upon a horizontal axis and bearing torch holding and adjusting means and pressure rollers between the same and the primary part to bear against the flange in opposition to the feed wheel.

50 8. A machine for trimming upstanding flanges by means of gases, having a center support, a depending self-propelled structure, and means for supporting the same from the center with freedom to swing about the center and to move in and out with reference thereto as the depending structure travels along the flange, said depending structure comprising a primary part including a vertical drive shaft with a feed wheel upon its lower end to operate along one side of the flange, an arm connected by horizontal and vertical pivots to the primary part and bearing pressure wheels in downwardly projecting relation to bear upon the flange in opposition to said feed wheel, and torch

adjusters and a torch carried by said arm in rear of the pressure wheels and urging the same by their weight against the flange.

9. A machine for trimming upstanding flanges by means of gases, having a center support, a depending self-propelled structure and means for supporting the same from the center with freedom to swing about the center and to move in and out with reference thereto as the depending structure travels along the flange, said depending structure comprising two flexibly connected opposed parts embracing the flange between them and including a driven feed wheel, and a torch mounted upon one of said opposed parts in position to deliver its jets against the flange near the central vertical plane of the feed wheel.

10. Apparatus of the character described comprising a center support, an arm mounted to swing about said support, and a depending torch-bearing and guiding structure carried by said arm in such manner as to be capable of free movement toward and from the center, said depending structure comprising outer and inner parts, the outer part including a vertical feed shaft bearing a driving wheel to travel upon one side of a flange or guide, and the inner part being flexibly jointed to the outer part and having a pair of pressure rollers to bear upon the other side of the flange in opposition to the feed wheel, and torch-holding and adjusting means carried by said flexibly jointed part.

11. Apparatus of the character described comprising a center support, an arm mounted to swing about said support, and a depending torch-bearing and guiding structure carried by said arm in such manner as to be capable of free movement toward and from the center, said depending structure comprising outer and inner parts, the outer part including a vertical feed shaft bearing a driving wheel to travel upon one side of a flange or guide, and the inner part being hinged on a horizontal axis and carrying a pair of gravity-urged pressure rollers to bear upon the other side of the flange in opposition to the feed wheel, and torch-holding and adjusting means carried by said hinged inner part.

12. Torch-cutting apparatus, comprising a center support, a radial arm mounted to swing about said support, a carriage freely movable lengthwise on said arm, a bracket projecting downward from said carriage, a vertical shaft journaled in said bracket, a feed wheel connected with the lower end of said shaft, a motor on the carriage, a shaft driven by said motor extending downward on the carriage at one side of the arm, and a short transverse shaft geared to the proximate ends of said vertical shafts.

WORTHY C. BUCKNAM. 130
